GRASS GUARD FOR A SPRINKLER

Gaylord J. Harness, 9051 Amboy St.,
Sun Valley, Calif. 91352

Filed June 9, 1969, Ser. No. 17,610

Term of patent 14 years

Int. Cl. D23—01

U.S. Cl. D23—7

Fig. 1

Fig. 2

Fig. 3

Fig. 4

Fig. 5

Fig. 6

FIG. 1 is a rear perspective view of a grass guard for a sprinkler showing my new design;

FIG. 2 is a rear elevational view thereof;

FIG. 3 is a side elevational view thereof;

FIG. 4 is a front elevational view thereof;

FIG. 5 is a top plan view thereof; and

FIG. 6 is a bottom plan view thereof.

I claim:

The ornamental design for a grass guard for a sprinkler, substantially as shown.
